10 Claims

ABSTRACT OF THE DISCLOSURE

Use of 2,4-diamino-6-substituted-s-triazines for inducing depressant effects in animals.

This application is a continuation-in-part of copending application Ser. No. 498,116, filed Oct. 19, 1965 and now abandoned.

BACKGROUND OF THE INVENTION

This invention relates to a method of inducing depressant effects in animals using certain s-triazines. More particularly it relates to the use of certain s-triazines as analgesics, muscle relaxants, anticonvulsants and tranquilizers and to pharmaceutical and veterinary compositions containing such triazines.

A considerable number of naturally occurring alkaloids and synthetic chemicals are available as useful analgesics, anticonvulsants and muscle relaxants. Repeated administration of many such analgesics creates the potential danger of drug addiction. The need for effective analgesics which minimize the hazards of drug addiction has long been recognized.

SUMMARY OF THE INVENTION

It is an object of the present invention to provide a novel method for inducing depressant effects in mammals. These depressant effects include sedative, analgesic, muscle relaxant, anticonvulsant and tranquilizing effects. Another object of the invention is to provide a novel method of pain control with minimum hazard of drug addiction. Yet another object is to provide a novel method for inducing depressant effects in mammals with certain 2,4-diamino-6-substituted-s-triazines. The provisions for supplying the art with novel pharmaceutical and veterinary compositions capable of inducing neurological depressant effects in mammals forms another object.

These and other objects are accomplished by administering to a mammal an effective dosage of a 2,4-diamino-6-substituted-s-triazine of the formula

wherein:

R is alkyl of 1-5 carbon atoms or phenyl and R₁ is hydrogen or alkyl or 1-5 carbon atoms; R₂ is alkyl of 1-5 carbon atoms or hydrogen and R₃ is alkyl of 1-5 carbon atoms, phenyl or chlorophenyl; and

—CN; —OCN; —H; —OH₂; —SCN; —SNH₂; —N₃; (Q)_m

2

where Q is trichloroacetic acid or 2,4,6-trichlorophenol and m is 0 or 1;

where R₄ is alkyl of 1-4 carbon atoms;

where alkyl is of 1-3 carbon atoms;

15 where alkyl is of 1-3 carbon atoms;

—NHN=R₅ where R₅ is benzylidene or

25 where R₆ is alkyl of 1-3 carbon atoms;

—NH—NH—R₇ where R₇ is hydrogen,

30 where R₈ is alkyl of 1-4 carbon atoms;

—S—R₉ where R₉ is cyanoalkyl of up to 4 carbon atoms or alkylthio of 1-3 carbon atoms;

35 where R₁₀ is alkyl of 1-3 carbon atoms;

40 where R₁₁ is hydrogen or alkyl or 1-3 carbon atoms;

45 where alkyl is of 1-3 carbon atoms; or —Cl.

Representative species of the above s-triazines are:

- 55 (1) 2-isopropylamino-4-ethylamino-6-piperazino-s-triazine
- (2) 2,4-bis-(anilino)-6-cyano-s-triazine
- (3) 2,4-bis-(dimethylamino)-6-cyanato-s-triazine
- (4) 2-dimethylamino-4-p-chlorophenyl-s-triazine
- (5) 2,4-bis-(isopropylamino)-6-aminoxy-s-triazine
- (6) 2-ethylamino-4-isopropylamino-6-aminoxy-s-triazine
- (7) 2-methylamino-4-(1,1-dimethylpropyl)amino-6-thiocyanato-s-triazine
- 60 (8) 2-isopropylamino-4-ethylamino-6-aminothio-s-triazine
- (9) 2-tert-butylamino-4-ethylamino-6-azido-s-triazine, trichloroacetic acid adduct
- (10) 2-isopropylamino-4-ethylamino-6-azido-s-triazine, trichloroacetic acid adduct
- 65 (11) 2-isopropylamino-4-ethylamino-6-azido-s-triazine, 2,4,6-trichlorophenol adduct

- (12) 2-methylamino-4-(1,1-dimethylpropyl)amino-6-azido-s-triazine
- (13) 2-propylamino-4-ethylamino-6-azido-s-triazine
- (14) 2-methylamino-4-propylamino-6-azido-s-triazine
- (15) 2,4-bis-(diethylamino)-6-diethoxyphosphinyl-s-triazine
- (16) 2-isopropylamino-4-ethylamino-6-diethoxyphosphinyl-s-triazine
- (17) 2,4-bis-(isopropylamino)-6-methoxycarbonyl-s-triazine
- (18) 2-isopropylamino-4-methylamino-6-ethylthio(thiocarbonyl)-s-triazine
- (19) 2-ethylamino-4-isopropylamino-6-(5-chloromethyl-1,2,4-oxadiazol-3-yl)-s-triazine
- (20) 2,4-bis-(isopropylamino)-6-benzylidene-hydrazino-s-triazine
- (21) 2,4-bis-(ethylamino)-6-(3-hydroxy-1-methylbut-2-enylidene)hydrazino-s-triazine
- (22) 2-anilino-4-dimethylamino-6-hydrazino-s-triazine
- (23) 2-ethylamino-4-isopropylamino-6-hydrazino-s-triazine
- (24) 2,4-bis-(dimethylamino)-6-[2-(2,2,2-trichloro-1-hydroxyethyl)hydrazino]-s-triazine
- (25) 2,4-bis-(isopropylamino)-6-[2-(2,2,2-trichloro-1-hydroxyethyl)hydrazino]-s-triazine
- (26) 2,4-bis-(ethylamino)-6-(2-benzoylhydrazino)-s-triazine
- (27) 2,4-bis-(dimethylamino)-6-(2-dimethoxythiophosphinyl-1-hydrazino)-s-triazine
- (28) 2,4-bis-(ethylamino)-6-(1-cyanopropylthio)-s-triazine
- (29) 2-diethylamino-4-ethylamino-6-methyldithio-s-triazine
- (30) 2-ethylamino-4-tert-butylamino-6-(3-cyano-3-methyl-1-triazeno)-s-triazine
- (31) 2,4-bis-(ethylamino)-6-(5-methyl-2-thiazolyl)-s-triazine
- (32) 2-isopropylamino-4-propylamino-6-(1-amino-1-hydroxyiminomethyl)-s-triazine
- (33) 2,4-bis-(isopropylamino)-6-(1-amino-1-ethoxyiminomethyl)-trans-s-triazine
- (34) 2,4-bis-(isopropylamino)-6-(1-amino-1-ethoxyiminomethyl)-cis-s-triazine
- (35) 2,4-bis-(isopropylamino)-6-(1-benzoyl-1-cyano-1-ethoxycarbonylmethyl)-s-triazine
- (36) 2-tert-butylamino-4-ethylamino-6-chloro-s-triazine

Compositions according to the present invention also comprise a pharmaceutical carrier which may either be solid material or a liquid. Preparations for oral administration can be liquids or solids or any combination of these forms, such as syrups, elixirs, powders, capsules, or tablets. Preparations for administration of the active agent in unit dose form can be powders, compressed tablets, or a powder enclosed in a suitable capsule of absorbable material such as gelatin. The powders or compressed tablets may also comprise suitable excipients and/or diluents such as starch, lactose, stearic acid, magnesium stearate, dextrin or polyvinylpyrrolidone.

Preparations for topical application may be in the form of a liquid, a powder, a salve, or as a aerosol.

Preparations for parenteral administration may be sterile solutions or suspensions in liquids such as water, physiological saline, benzyl alcohol, ethyl oleate, methylcellulose, dimethyl sulfoxide or other liquid excipients known in the pharmaceutical and veterinary formulation art.

Any of the above preparations may contain the triazines of the invention or may contain in addition other pharmaceutically active agents. For example, for topical application it may be desirable to include a germicide and/or a fungicide.

The unit dosage or therapeutically effective quantity of the triazines used according to this invention as analgesics, muscle relaxants, anticonvulsants and/or tran-

- quilizers can vary over wide limits. For oral or parenteral administration in some cases, as little as 0.01 milligram of the active material per kilogram of body weight can be effective in the reduction of pain or in effecting sedation and muscle relaxation, while seldom will a dosage in excess of about 500 milligrams per kilogram of body weight be required. In general, for oral administration, the effective dosage will be from about 1.0 to 200 milligrams per kilogram of body weight, while for parenteral administration, the effective dosage will be from about 0.10 to about 100 milligrams per kilograms of body weight. Each dosage unit form—each capsule, tablet, ampoule, or prescribed dose—can contain from about 1 percent to about 95 percent of active material, based upon the total weight of the formulation and preferably contains from about 2.5 percent to about 50 percent of the active material, on the same basis. Of course, it is possible to administer the therapeutics without the use of a pharmaceutical carrier.
- 20 The therapeutic agents used according to the invention can be administered either prior to or after the onset of the condition to be treated, such as when they are used as: analgesics for the amelioration of pain; motor depressants or tranquilizers to relieve nervous tension; central depressants to reduce hyperexcitability and induce sedation; or as muscle relaxants for relief from pain and discomfort of disorders involving muscle spasms.

PREPARATION

- 30 The s-triazines of this invention may be prepared by conventional methods known in the art for preparing these types of triazines. The following description is illustrative of some of the methods of preparation. The starting materials for the s-triazines of this invention are cyanuric chloride or 2,4,6-tris-(trichloromethyl)-s-triazine. By successive replacement of the chloro or trichloromethyl groups of these compounds, the groups depicted in Formula I are introduced.
- 35 Thus, the amino groups, $—NRR_1$, $—NR_2R_3$ and piperazine, may be introduced by the conventional methods known in the art, e.g., as described by Elderfield, R. C., Heterocyclic Compounds, N.Y., John Wiley and Sons, 1961, vol. 7, pp. 669-671.
- 40 The cyano group may also be introduced by known methods, e.g., by reaction of a chloro-s-triazine with sodium cyanide in the presence of base such as trimethylamine. It is preferred that the sodium cyanide be added as an aqueous solution to a dioxane solution of the triazine. The method described in U.S. 3,234,225 may also be used.
- 45 The cyanogen group ($—OCN$) may be introduced by reaction of a hydroxy-s-triazine with cyanogen chloride in an ether solvent in the presence of a base such as triethylamine.
- 50 The aminoxy group ($—ONH_2$) may be introduced by the method described in German Pat. 1,232,588 while the thiocyanato group ($—SCN$) may be introduced by the methods described in U.S. 3,120,468.

The aminothio group ($—SNH_2$) is introduced by reaction of a mercapto-s-triazine with sulfonyl chloride in a halogenated hydrocarbon diluent, followed by reaction with ammonia gas.

The azido group may be introduced by the methods described in U.S. 3,328,400 while the trichloroacetic acid and 2,4,6-trichlorophenol adducts of these azido-s-triazines are readily prepared by mixing the azido-s-triazine with trichloroacetic acid or 2,4,6-trichlorophenol in equimolar amounts.

The dialkoxyphosphinyl groups ($—PO(OR_4)_2$) may be introduced by reaction of a chloro-s-triazine with a dialkyl ester of phosphoric acid in an aromatic solvent in the presence of sodium.

The alkoxycarbonyl group may be introduced by hydrolysis of a cyano-s-triazine with sodium hydroxide followed by alkylation with an appropriate dialkyl sulfate,

The $-\text{C}(\text{S})\text{S}$ -alkyl group may be introduced by reaction of a trichloromethyl-s-triazine with NaSH in dimethylformamide followed by reaction with an alkyl bromide.

The 5-chloromethyl-1,2,4-oxadiazol-3-yl group may be introduced by refluxing a mixture of a triazinyl carboxamide oxime and chloroacetyl chloride in benzene. The triazinyl carboxamide oxime may be prepared by refluxing a mixture of a cyano-s-triazine and hydroxylamine hydrochloride in an aqueous alcoholic solution of sodium hydroxide.

The first member of the $-\text{NHNH}-\text{R}_7$ group, the hydrazino group, may conveniently be introduced by refluxing a mixture of a chloro-s-triazine and hydrazine hydrate in a lower alkanol diluent. The remaining members of this group are prepared by reacting the hydrazino-s-triazine: with chloral (R_7 is $-\text{CH}(\text{OH})\text{CCl}_3$); with benzoyl chloride in the presence of triethylamine (R_7 is phenylcarbonyl); and with a dialkoxy thiophosphoryl chloride in the presence of triethylamine

The $-\text{NHNH}-\text{R}_5$ group may be introduced (R_5 is benzylidene) by reaction of a hydrazino-s-triazine with benzaldehyde. The remaining members may be introduced by reacting an appropriate 1,3-diketone

with a hydrazino-s-triazine.

The first member of the $-\text{S}-\text{R}_9$ group, R_9 is cyanoalkyl, may be introduced by reacting a mercapto-s-triazine with a chloroalkyl cyanide in an aqueous solution of sodium hydroxide and acetone at moderate temperatures. The other member of this group, R_9 is alkylthio, may be introduced by reacting a mercapto-s-triazine with a compound of the formula $\text{alkyl-S-SO}_3\text{Na}$ in an aqueous solution of sodium hydroxide.

The $-\text{N}=\text{N}-\text{R}_{10}\text{CN}$ group may be introduced by refluxing a mixture of an azido-s-triazine and sodium cyanide in a lower alkanol, cooling the mixture and adding an appropriate dialkyl sulfate.

The 5-methyl-2-thiazolyl group may be introduced by refluxing a mixture of a thiocarbamoyl-s-triazine, isopropyl alcohol and chloroacetone.

The $-\text{C}(\text{NH}_2)=\text{NO}-\text{R}_{11}$ group (R_{11} is hydrogen) may be introduced by refluxing a cyano-s-triazine with hydroxylamine hydrochloride in an aqueous alcoholic solution of sodium hydroxide. Reaction of a cyano-s-triazine with an O-alkyl hydroxylamine ($\text{H}_2\text{NOR}_{11}$) in a lower alkanol solvent in the presence of hydrogen sulfide introduces the remaining members of this group.

The

group may be introduced by reacting a trimethylammonium-s-triazine with an alkyl ester of benzoylcyanooacetic acid in an aqueous solution of sodium hydroxide.

The following examples are illustrative of the preparation of some of the s-triazine of this invention.

EXAMPLE I

5 18.3 g. 2,4-bis-dimethylamino-6-hydroxy-s-triazine and 7 g. cyanogen chloride were added to 100 ml. tetrahydrofuran and the mixture cooled to 0° C . After adding 10.6 g. triethylamine, the mixture was stirred for 1 hour at room temperature and then evaporated under vacuum. 10 The residue was taken up with water and methylene chloride. After distilling off the solvents there was obtained 18.1 g. of the colorless oil, 2,4-bis-dimethylamino-6-cyanato-s-triazine.

EXAMPLE II

15 To a stirred solution of 72 g. of (2,4-bis-(isopropylamino)-6-trimethylammonium-s-triazinyl)-chloride in 50 ml. of water, was added 32.5 g. of sodium azide at room temperature. The crystalline precipitate which formed, was allowed to stand for 1 hour. After filtering, washing and drying, 51 g. of 2,4-bis-(isopropylamino)-6-azido-s-triazine, M.P. $94-95^\circ\text{ C}$, was obtained.

PREFERRED EMBODIMENTS

20 While the s-triazines of Formula I show some depressant effects in mammals, there are differences both quantitative and qualitative exhibited by individual members of the class. Especially preferred depressants because of their activity as analgesics, muscle relaxants, anticonvulsants, and/or tranquilizers are the s-triazines of Formula I wherein R and R_2 which may be the same or different, are alkyl of 1-5 carbon atoms, R_1 and R_3 , which may be the same or different, are hydrogen or alkyl of 1-5 carbon atoms and X is $-\text{OCN}$ or $-\text{N}_3\cdot(\text{Q})_m$ where Q is trichloroacetic acid or 2,4,6-trichlorophenol and m is 0 or 1.

Preferred s-triazines within this subclass are:

- 24-bis-(dimethylamino)-6-cyanato-s-triazine
 2-tert-butylamino-4-ethylamino-6-azido-s-triazine, trichloroacetic acid adduct
 2-isopropylamino-4-ethylamino-6-azido-s-triazine, trichloroacetic acid adduct
 45 2-isopropylamino-4-ethylamino-6-azido-s-triazine, 2,4,6-trichlorophenol adduct
 2-methylamino-4-(1,1-dimethylpropyl)amino-6-azido-s-triazine
 2-propylamino-4-ethylamino-6-azido-s-triazine
 2-methylamino-4-propylamino-6-azido-s-triazine

The following examples are presented to illustrate certain pharmacological responses induced by triazine compositions of the invention. These examples should in no way be regarded as limiting the scope of the invention.

The results of the various pharmacological responses tested are shown in Table I.

¹ Numbers correspond to numbered triazines in cols. 2 and 3.**Analgesic response (a)**

The presence of an analgesic effect was identified as an absence of a struggling or phonating response to a manual pinch of the tail of treated mice. The laboratory white mice for each treatment were placed in individual compartments. The mice were orally intubated with the test compound at the dosage of 500 milligrams per kilogram, and 15 minutes, 1 hour, 2 hours, 4 hours and 24 hours after treatment a pinch of the tail was applied to each mouse. Any compound inducing an analgesic response in 50 percent of the mice at any of these test intervals was considered active in this test. Some of the compounds were tested at lower dosages.

While the exact safety factor has not been evaluated for all compounds of the invention, it has been found that the effective analgesic dose of the triazines of the invention is considerably lower than the toxic dose (LD₅₀).

Muscle relaxant response (b)

As in (a) mice were orally intubated with the test compound and the muscle relaxant effects of the compounds were evaluated. The procedure for assessing skeletal muscle relaxant activity involves an evaluation of passivity, flaccidity and pinnal reflex blockage. Passivity is defined as an absence of the struggle behavior of the animal when manipulated manually and may indicate skeletal muscle relaxation, central depression, tranquilization, paralysis, or anesthesia. Flaccidity is measured by the decreased tonus of skeletal musculature and may indicate myorelaxant activity, central depression, or paralysis. The pinnal reflex is tested by touching the inner aspects of the ear with a fine wire to elicit a characteristic ear twitch. An impairment of this reflex suggests an inhibition of polysynaptic reflexes.

Analgesic response—Intraperitoneal (c)

The analgesic response was determined in laboratory white mice by injection of the triazines under test at an intraperitoneal dosage of 100 mg. per kg. The results were obtained by evaluation similar to that described for the Approximate Analgesic Dose—Oral. The compounds were rated on a one plus (+) to four plus (++++) scale. When 1-2 mice out of ten showed an analgesic response, a + rating was assigned; ++ indicated that 3-6 out of ten mice responded; +++ indicated that 7-9 out of ten responded; while a ++++ rating meant that all ten mice gave an analgesic response at the dosage tested.

Muscle relaxant—Tranquilization response (d)

The muscle relaxant effects, as expressed by passivity, flaccidity and pinnal reflex blockage, were assessed in

laboratory mice injected intraperitoneally with 100 mg./kg. of the test compound as in (b). In addition the tranquilizing effects of the compounds under test were evaluated by the pernicious preening test (Wilfond, J. G. et al. Fed. Proc. 19:20, 1960). The pernicious preening behavior was elicited by painting the rear of the mice with a pilocohesive dye. A violent unremitting tearing of the stiff, cohering strands of hair constitutes the pernicious preening behavior. Thirty minutes after injection, the pilocohesive dye was applied and the presence or absence of the compulsive behavior was noted for a 10 minute interval. The ratings for the muscle relaxant response are based upon the scale given in (c). Effective antagonism of pernicious preening is shown with the same scale as in (c). That is, + = 1-2 mice out of ten, ++ = 3-6 mice out of ten, +++ = 7-9 mice out of ten and ++++ = 10 mice out of ten responded. Some of these values for the individual triazines were determined at a dosage of 32 mg./kg. while the others were determined on the basis of ED₅₀ values, the dose at which 50 percent of the treated animals exhibit an effective response. These ED₅₀ values were then translated into the 1+ to 4+ scale by the following criteria: ED₅₀ values of 30-100 mg/kg = +, 10-30 mg./kg. = ++, 3-10 mg./kg. = +++ and <3 mg./kg. = +++.

Anticonvulsant response (e)

The test procedures used were maximal electroshock and antistrychnine assay methods. The test compound was intraperitoneally injected into laboratory mice and after 30 minutes the anticonvulsant activity was measured. The technique employed in the maximal electroshock method was essentially that of Swinyard, E. A., J. Amer. Pharm. Assoc. 38:201 (1949). The mice were subjected to an alternating current stimulus, about equal to three times the current necessary to produce maximal seizures, and prevention of the hindlimb tonic extensor phase was considered to be an effective anti-convulsant action. In the antistrychnine assay, the mice were intraperitoneally injected with the test compound and then were challenged with a lethal intraperitoneal dose of strychnine sulfate. Increase in survival time against the lethal action of strychnine of greater than three standard deviations of the control mean was considered an effective action. Anti-convulsant activity in these tests suggests skeletal muscle relaxation or efficacy against epileptic seizures. Effective antagonism of maximal electroshock seizure and antistrychnine activity are given on the same 1+ to 4+ scale as in (c). Some of these values for the individual triazines in the maximal electroshock seizure test were determined at a dosage of 100 mg./kg. while the others were determined on the basis of ED₅₀ values, the dose at which 50
